LAUNDRY BAG

Nettie Davison, Upland, Calif., assignor of one-half to Ernest Zukin and one-half to Sylvia Zukin, both of Los Angeles, Calif.

Application October 25, 1948, Serial No. 149,275

Term of patent 3½ years

(Cl. D58—2)

To all whom it may concern:

Be it known that I, Nettie Davison, a citizen of the United States, residing at Upland, in the county of San Bernardino, State of California, have invented a new, original, and ornamental Design for a Laundry Bag, of which the following is a specification, reference being had to the accompanying drawing, forming part thereof.

In the drawing:

Fig. 2 is a rear elevational view thereof; and

Fig. 3 is a fragmentary cross sectional view taken on the line 3—3 of Fig. 1.

I claim:

The ornamental design for a laundry bag, as shown.

NETTIE DAVISON.
